VALVE MECHANISM.

1,333,267.

Specification of Letters Patent.

Patented Mar. 9, 1920.

Application filed March 30, 1918. Serial No. 225,826.

To all whom it may concern:

Be it known that I, LEWIS A. MAPEL, a citizen of the United States, residing at the city of St. Louis and State of Missouri, have 5 invented a new and useful Valve Mechanism, of which the following is a specification.

This invention relates to improvements in valves.

10 An object of the invention is to provide an improved valve mechanism comprising a chamber having a plurality of inlet passages for admitting water into the chamber, and a valve for controlling each inlet passage, said valves being independently adjustable and capable of accurate and minute adjustment whereby the character or quality of the water discharged from said chamber through the outlet passage may be varied as desired; in combination with a single outlet passage from said chamber for conducting the water therefrom to any point of delivery, and a single valve for controlling the outlet passage.

25 Another object of the invention is to provide a valve mechanism of the character mentioned in which the inlet valves are independently and minutely adjustable in order to effect any desired variation in the 30 temperature or character or quality of the mixture produced by the water supplied through the different inlet passages; in combination with a single outlet passage for conducting the mixture to any desired point of delivery, a balanced valve for controlling the flow of water into and through the outlet passage, the novel form of controlling mechanism whereby the balanced valve may be moved to and locked in open position, and means for closing said valve under predetermined conditions.

35 A further object of the invention is to provide a valve mechanism comprising a casing or chamber in which the various valves are mounted and in which access may be had to the interior of the chamber for any desired purpose when the valves for the inlet passages thereto are closed.

40 Various other objects of general and specific nature and various advantages of the invention will appear from the following description in which reference is made to

the accompanying drawing, illustrating a preferred embodiment of the invention, and in which

55 Figure 1 is a view illustrating the valve casing and the valve for the outlet passage in section, the controlling mechanism for the outlet valve being in elevation.

Figure 2 is a sectional view illustrating one 60 of the valves having an inlet passage.

Figure 3 is a perspective view of the complete valve mechanism.

65 In the preferred embodiment shown, my improved valve mechanism comprises a casing or chamber 1 having a plurality of inlet passages 2, one of which is shown in Fig. 1 and another of which appears in Fig. 3. While I have illustrated a construction in which there are only two inlet passages, it is obvious that the number of inlet passages may be varied in order to take 70 water from any desired number of sources of supply.

75 Annular valve seats 3 are removably secured within the chamber 1 in proper position relative to the inlet openings so that the water entering the casing from the inlet passages is required to pass through said valve seats.

80 The valve seats 3 are supported in inclined positions so that the valves controlling the flow of the water therethrough may be moved to open position by the pressure of the water against the influent sides of 85 the valves and will be moved by gravity to closed positions when the pressure on the opposite sides of the valves becomes equalized or balanced, which occurs when the valve controlling the outlet passage from 90 the chamber 1 is closed. Each valve includes a member 4 and a coöperating member 5 between which the fiber ring 6 is retained.

95 These parts are arranged substantially as illustrated in Fig. 2 so that the fiber ring 6 will seat upon the valve seat 3 when the valve is closed. The members 4 and 5 are secured to a stem 7 which operates within a hole formed in a guide 8 supported by the valve seat 3. The upper portion of the stem 7 operates within a recess in an independently movable and adjustable member 9 having a hand wheel 10 on the outer end thereof, whereby said member may 100

be readily adjusted to different positions. The member 9 is screwed into a support 11 which is removably secured within an opening in the upper wall of the chamber 1. As shown the threads on the member 9 are so inclined that approximately a single turn of said member is sufficient to move the same the full extent of movement of which it is capable, the inner end of said member being arranged to contact with the hub of the member 4. Outward movement of the member 9 is limited by a flange 12 thereon which is arranged to abut against the inner end of the support 11.

From the foregoing it will be seen that movement of the valve to open position is limited by contact of the hub on the member 4 with the inner end of the member 9. The valve will be retained in open position so long as the water is permitted to flow from the chamber 1 through the outlet passage.

It is also an important feature that the valve structures including the fiber rings 6 are within the chamber 1 so that all the valves are subjected to the action of cold water and water of varying temperatures. I have found in practice that the valves are quickly deteriorated when subjected constantly to the action of warm or hot water and further that the life of the valves is greatly prolonged when subjected to the action of cold water, or to the action of water of varying temperature. The deposits which adhere to the valves which are subjected constantly to the action of hot water alone are removed or prevented when the valves are subjected to the action of water of varying temperatures. So, in the present invention the inlet valves are wholly within the chamber 1 on the effluent sides of the valve seats 3 so that when the supply of hot water is cut off, as frequently occurs, all of the inlet valves are subjected to the action of cold water, thus removing or preventing the accretion of deposits on the valves which would otherwise occur and prolonging the life of the valves.

It is apparent that by proper relative adjustment of the members 9 the flow of water through the several inlet passages 2 may be relatively varied, as by permitting a greater volume or quantity of water to pass through one of the valves than is permitted to pass through another. It is also clear that such variation may be quickly effected in order to change or alter the character or quality of the mixture resulting from the mixture of the water received from different sources of supply through different supply passages. When it is desired to reduce the quantity or volume of water entering through any inlet valve the member 9 for controlling such valve is adjusted to limit movement of the corresponding valve in position to permit

the desired limited quantity or volume of water to pass.

As shown, there is a single outlet passage 13 for conducting the water from the chamber 1. The flow of the water from the chamber 1 into the outlet passage is controlled by a single valve which, in the form shown, operates in an inclined plane to and from a valve seat 14, the same being in the form of a ring secured within the outlet opening from the chamber 1. The valve for the outlet opening comprises a central portion 15 having a flange 16 on its lower end and a flange 17 of corresponding size at its upper end. A fiber member 18 is secured to the under side of the flange 16 by a retaining member 19 having threaded engagement in the lower end of the valve body. The flange 17 operates within a chamber 20 removably secured in an opening in the upper wall of the chamber 1.

The outlet valve thus constructed is slideable upon a rod 21 extending through an appropriate mounting 22 at the lower side of the chamber 1 and having its upper end operating within a guide 23, constituting a part of the member supporting the guide 20. The rod 21 also operates through a guide 24 in connection with the valve seat 14 so that said rod is properly and accurately supported and guided in its movements.

Pressure is relieved from the chamber above the flange 9 through openings 25. A coil spring 26 encircles the rod 21 above the valve and has its lower end bearing against a valve 27 secured to the rod 21 and arranged to seat against the upper end of the outlet valve. When the rod 21 is raised the valve 27 is moved away from the outlet valve, thus opening the passages 25 and permitting the outlet valve to move to open position.

A spring 28 encircles the rod 21 below the outlet valve, the same having its upper end bearing against the lower end of the valve 110 and its lower end bearing against an abutment 29 on the stem. As a result of this construction the spring 28 is compressed when the rod is raised and the power of the spring 28 quickly raises the outlet valve 115 to open position, such movement being permitted when the pressure is relieved from above the valve through the openings 25. The flange 17 is provided with a vent 17^a opening into the chamber above the flange 120 so that when the valve is actuated to closed position under impulse of the spring 26, water may enter the chamber above the flange 17 thus enabling the valve to be moved easily and freely by the spring.

From the foregoing it will be apparent that the movement of the outlet valve is not impeded by the water pressure in the chamber in which the valve operates, because said valve is balanced, the pressure being equal

in both directions, that is against the flange 16 at the lower end of the valve and the flange 17 at the upper end of the valve. It is also apparent that the inlet valve will be closed when released by the locking mechanism, just as rapidly as water passes through the vent 17^a to fill the space above the valve when the same moves toward closed position, and that the rapidity of said movement of the valve is in proportion to the size of the vent permitting such passage of the water. For regulating the flow of the water through the vent passage 17^a an adjustable screw 17^b is provided, the same being supported by an appropriate bracket or support in connection with the valve. The screw is adjustable toward and away from the vent opening so that the rapidity with which the water may enter the space above the valve may be controlled and varied as desired.

The outlet valve is equipped with mechanism whereby the same may be easily moved to open position and with coöperating devices for holding or locking the same in open position. The coöperating mechanism mentioned is intended to be automatically released after a predetermined quantity of water has passed through the outlet valve into the receptacle for receiving the same. In the embodiment illustrated the mechanism for releasing or unlocking the outlet valve is under control of a float device.

As shown a support 30 for the operating and locking mechanism for the outlet valve is secured to the lower wall of the chamber in which the valve is mounted. A lever 31 is mounted on a pivot 32 in said support, preferably below the rod 21. The lever 31 carries a roller 33 adjacent to the end of the rod 31 so that when said lever is raised the roller will operate against the end of the rod and raise the rod, thereby opening the outlet valve. The roller makes the operation of the valve stem free and easy, since the roller can turn upon its pivot and thereby accommodate itself to the movement of the parts. A lever 34 mounted on a pivot 35 has one end connected with a link 36 and its opposite end connected with a link 37. The link 36 is also pivotally connected with an arm 38 rigid with the lever 31, said parts occupying positions approximately as illustrated in Fig. 1 when the outlet valve is closed. When the lever 31 is raised as required to open the outlet valve, the pivots connecting the link 36 with the lever 34 and with the arm 38 are on a straight line parallel with the axis of the rod 21, as a result of which the lever 31 will be locked in its raised position, thereby retaining the outlet valve open. In order to permit the lever 31 to return to its lower position, as shown, and thereby enable the outlet valve to close, it is necessary to break the toggle lock by

operating the lever 34 effectively to move the pivotal connection between the same and the link 36 out of alinement with the pivot 35 and the pivot connecting the link 36 with the arm 38. When the toggle lock 70 is thus broken the power of the spring 26 presses the outlet valve to closed position.

At this point it is appropriate to advert again to the inlet valves which, as previously described, are held open by the pressure of the water when the outlet valve is open. However, when the outlet valve is closed the chamber 1 becomes filled with water on both the influent and effluent sides of the inlet valves. Thus the pressure against 75 both sides of the inlet valves becomes balanced when the outlet valve is closed, so that said inlet valves are permitted to be moved by gravity to closed position. The inlet valves also may be held in their closed position by proper adjustment of the members 9, and when the inlet valves are retained in closed position the chamber in which the outlet valve is mounted may be opened to afford access to the interior of the entire 80 chamber in order to enable any of the parts to be removed or replaced or repaired.

Downward movement of the lever 31 is limited by an adjustable abutment 39 which is in the form of a screw carried by an arm on the support 30; and upward movement of said lever is limited by a similar abutment 40 which is also carried by an arm of the support 30. Extent of movement of the lever 31 and the link 36 toward locking position is limited by an adjustable abutment 41 which, preferably, is in the form of a screw adjustable in the support 30. The provision of the adjustable abutments 39 and 40 to limit movement of the lever 31 prevents any 95 undue strain being exerted upon any of the parts connected with the lever by careless or unnecessarily forcible operation, as would otherwise occur.

A lever 42 is pivotally supported at 43 and has one end connected with the link 37 and the opposite end supporting a bar 44. A float 45 is within a chamber 46 which is arranged to receive water from the outlet pipe 13, or the receptacle into which the water is discharged in a well understood manner. A rod 47 is connected with the float and is adjustably secured to the bar 44 by a retaining device comprising a bracket 48 and a detent 49.

From the foregoing description of the connection between the float and the locking devices of the outlet valve, it is apparent that when the weight of the float is supported from the lever 42 and the connections 100 therefrom to the lever 31 the toggle lock, comprising the lever 34 and the link 36, will be moved certainly to locking position when the lever 31 is raised. This result is attained because the weight of the float actu- 105 110 115 120 125 130

ates the lever 34 in a direction to move the pivot connecting the same with the link 36 to locking position toward the abutment 41. This result is attained without the use of 5 springs or other actuating devices usually employed for this purpose. Also, when the water in the chamber 46 rises sufficiently to raise the float, the lever 42 will be operated in a direction to break the toggle lock by 10 moving the pivot connecting the lever 34 with the link 36 out of alinement with the other two pivots. When this occurs the outlet valve will be closed by the expansion of the spring 26 which was under compression 15 when the outlet valve was open.

The rod 47 which is in connection with the float may be connected with the bar 44 in any point of various selected positions so that by changing the position of the float 20 in its relation to the bar 44 the quantity of water required to actuate the float and unlock the outlet valve may be varied at will. Thus by connecting the rod 27 in a lower position upon the bar 44 and thereby lowering 25 the float in the chamber 46, a comparatively small quantity of water will raise the float and unlock the outlet valve; whereas by connecting the rod 47 to the bar 44 in any higher position a greater quantity of 30 water may pass the outlet valve before the float will be raised and the outlet valve unlocked. And this variation may be effected within any desired limits. The connecting device 48-49 which is conventionally illustrated in Fig. 1 is conveniently operable so 35 that this adjustment of the float in any of the selected positions may be made quickly and without the use of any special appliances or tools for that purpose.

40 Also, it will be observed that when the float is actuated upwardly by the water to unlock the locking mechanism of the outlet valve, the float is raised out of the water by the movement of the parts under the 45 impulse of the valve rod 21 actuated by the spring 26 which closes the outlet valve.

The raising of the float out of the water dispenses with the vibration of the float and the other parts in connection therewith from 50 the surging of the water in the tub or receptacle into which the water is delivered, so that irrespective of the disturbance of the water, the valve mechanism remains stationary and undisturbed.

55 Valve mechanism of the character described possesses numerous advantages which are apparent from the foregoing description, and I have not attempted to mention more than a few of them. By so doing, 60 I do not restrict or limit myself, nor do I confine myself to identical or specific features of construction, since it is perfectly apparent that there may be numerous variations in the construction and arrangement of 65 the various elements without departing in

the least from the broader spirit of the invention.

Having described one embodiment of my invention, what I claim and desire to secure by Letters Patent, is:—

70 1. Valve mechanism, comprising a casing forming a chamber, pipes opening into the chamber for admitting water into the chamber, obliquely inclined valve seats within the chamber, obliquely inclined puppet valves within the chamber movable obliquely to and from said valve seats to close and to open the openings from said pipes, and being movable to open position by the pressure of the water in the pipes, adjustable devices adjacent to one side of the casing for minutely varying the extent of movements of said valves independently of each other to vary relatively the quantity of water entering said chamber from said pipes, an outlet passage from said chamber, a valve also within the chamber for controlling the outlet passage, manipulative locking mechanism for said last-named valve operable to move said last-named valve to and lock the same 80 in open position, said locking mechanism being on the same side of the casing as said devices for varying extent of movement of the first-named valves, and mechanism under control of the water that has passed said 85 last-named valve to unlock said locking mechanism when a predetermined quantity of water has passed said valve.

90 2. Valve mechanism; comprising a chamber arranged to contain water, an outlet passage for conducting the water from the chamber, a valve for opening and closing the outlet passage, a lever for actuating the valve to open position, connections for locking said lever in position to hold the valve 100 open, a float device under control of the water that has passed the valve arranged to actuate said connections to unlock said lever, and an actuator for actuating said lever and said connections to position to raise the float 110 device out of the water when said lever is unlocked, whereby the float device is left undisturbed by any variation in the level or any disturbance of the water that has passed said valve.

115 3. Valve mechanism, comprising a chamber, an outlet passage for conducting water from the chamber, a valve for opening and closing said passage, a valve stem, a spring co-operating with said valve stem for moving said valve to open position, a lever for actuating said valve stem to cause said spring to move the valve to open position, mechanism for locking said lever in position to hold the valve in open position, a float device under 120 control of the water that has passed the valve arranged to unlock said locking mechanism when a predetermined quantity of water has passed the valve, and an actuator for actuating the valve stem to move said 130

lever and said locking mechanism to position to raise the float device out of the water when the locking mechanism is unlocked.

4. Valve mechanism, comprising a chamber having an outlet passage, a puppet valve which is balanced as to the pressure of the water in the chamber for opening and closing said passage, a guide chamber in which one end of said valve operates, a vent passage through said valve for admitting water from the chamber into the guide chamber, a device for varying the quantity of water that may pass through said vent passage, a valve stem, a spring coöperating with said valve stem for moving the valve to open position, mechanism for actuating the valve stem to and locking the same in position to cause said spring to hold the valve open, a float device under control of the water that has passed the valve arranged to unlock the locking mechanism when a predetermined quantity of water has passed the valve, and an actuator for actuating said valve stem and thereby the locking mechanism to position to raise the float device out of the water when the locking mechanism is unlocked.

5. Valve mechanism, comprising a chamber, an outlet passage for conducting water from the chamber, a puppet valve balanced as to the pressure of the water in the chamber for opening and closing said passage, a guide chamber in which one end of said valve operates, a vent passage through said valve for admitting water from the chamber into the guide chamber, a valve stem, a spring coöperating with said valve stem for moving the valve to open position, a lever for holding said valve stem in position to hold the valve open, a float device controlling said lever and arranged to move said lever to position to release said valve when a predetermined quantity of water has passed the valve, and an actuator for actuating said valve stem to close said valve and to move said lever to position to raise the float device out of the water when said float device has moved said lever to position to release the valve as aforesaid.

50 6. Valve mechanism, comprising a water chamber, an outlet passage for conducting water from the chamber, springs at opposite ends of said valve, devices for causing the spring at one end of said valve to move the valve to open position, locking mechanism coöperating with said devices to lock the valve in open position, and a float device for releasing said locking mechanism

after a predetermined quantity of water has passed said valve leaving the spring at the opposite end of the valve free to press the valve to closed position.

7. Valve mechanism, comprising a water chamber, an outlet passage for conducting water from the chamber, springs at opposite ends of said valve, devices for causing the spring at one end of said valve to move the valve to open position, locking mechanism coöperating with said devices to lock the valve in open position, and a float device for releasing said locking mechanism after a predetermined quantity of water has passed said valve leaving the spring at the opposite end of the valve free to press the valve to closed position, and to raise the float device out of the water whereby the float device is left undisturbed by any variation in the level or disturbance of the water that has passed the outlet valve.

8. Valve mechanism, comprising a chamber having inlet passages, an outlet passage for conducting the water from the chamber, a valve controlling the outlet passage mechanism for locking the valve in open position to permit the water to flow from the chamber into the outlet passage, a float device under control of the water that has passed the valve for unlocking the locking mechanism, and means for actuating the valve to closed position and for actuating the locking mechanism to raise the float device out of the water, whereby the float device and other parts are left undisturbed by the surging of the water.

9. Valve mechanism, comprising a chamber, an inlet passage for delivering water into the chamber, an outlet passage for conducting the water from the chamber, a valve for opening and closing the outlet passage, mechanism for actuating the valve to open position and locking the same in open position to permit a continuous flow of water through the outlet passage, a float device under control of the water that has passed the valve arranged to unlock the locking mechanism when a predetermined quantity of water has passed the valve, and an actuator for actuating the locking mechanism to position to raise the float device out of the water when the locking mechanism is unlocked, whereby the float device is left undisturbed by any variation in the level or disturbance of the water that has passed the outlet valve.

LEWIS A. MAPEL.
